UNITED STATES PATENT OFFICE.

DAVID N. ROBERTSON, OF LYNN, MASSACHUSETTS, ASSIGNOR OF ONE-HALF TO PERCY F. MUNSEY, OF SWAMPSCOTT, MASSACHUSETTS.

BUFFING-MACHINE FOR PARTS OF BOOTS AND SHOES.

1,073,288.

Specification of Letters Patent. Patented Sept. 16, 1913.

Application filed April 8, 1911. Serial No. 619,666.

To all whom it may concern:

Be it known that I, DAVID N. ROBERTSON, a citizen of the United States, residing at Lynn, county of Essex, State of Massachusetts, have invented a certain new and useful Improvement in Buffing-Machines for Parts of Boots and Shoes, of which the following is a specification, reference being had therein to the accompanying drawings.

10 My invention has for its object an improved buffing machine by means of which parts of boots and shoes, such for instance as toe caps and counters may be buffed and finished after being skived.

15 In my machine, the pieces of stock are held in place in the matrix by causing a partial vacuum underneath the stock so that it is pressed firmly in the depression in the matrix by air pressure, while it is being presented to the buffing wheel. It results that the finished work is not marred or scratched, and the corners are not broken off, but the work is left intact, smooth and well finished.

20 Another important advantage of my invention has to do with the fact that in manufacturing these goods, it is frequently desirable to bevel the edges without reducing the thickness of the center of the piece. By cutting the cavity in the matrix of my machine 25 deeper than the thickness of the finished piece this may be accomplished by the use of my machine as the air pressure presses the piece of stock to the bottom of the matrix and the operating tool does not touch 30 the work except at the edges.

35 In the accompanying drawings I have also shown the stock as being operated upon by a sand paper roll for the purpose of scouring or buffing, but other tools or operating 40 mechanism may be employed. Accordingly I have used the word "tool" in the accompanying specification to include any device employed to operate upon stock while held in place in a matrix.

45 The invention will be fully understood from the following specification taken in connection with the accompanying drawings, and the novel features thereof are pointed out and clearly defined in the claims 50 at the close of this specification.

55 Referring to the drawings, Figure 1 is an elevation of a machine embodying my invention. Fig. 2 is a plan view of the rotary matrix. Fig. 3 is a section on line 3—3 Fig. 1. Fig. 4 is a section through the matrix at

the point of contact with the sand paper roll, said view being on a somewhat enlarged scale. Fig. 5 is a front elevation of the top part of the machine showing the means for changing the location of the operating tool 60 as it wears.

Referring to the drawings, the frame of the machine is indicated at A. It is of any convenient shape adapted to support the various working parts. In the frame A is 65 supported a main shaft B on the end of which is located a cylindrical matrix C capable of rotation. In practice I form the matrix C with a hub 11 which extends over the end of the shaft B and is secured thereto 70 in any suitable manner, as, for instance, by a set screw 12. The matrix C is preferably formed with a wall 16 on the side toward the hub (i. e. the left hand side as seen in Fig. 3) and is hollow and unobstructed 75 interiorly so that the coöperating suction box which will be described later can be supported inside the matrix and the matrix will still be free to rotate. The matrix C is covered with a removable facing 13 of soft 80 metal, as for instance lead, in which one or more cavities 14 may be readily formed to receive the back side of the work to be operated upon. This facing of lead 13 is secured on one side by sliding under a flange 85 52 (see Fig. 4) on the periphery of the matrix and on the other by small screws 53. This makes it possible to change the machine for different sizes or different articles 90 by removing the lead facing and replacing 95 it by a new one. The cavities are conveniently formed by marking out the outline of the counter or tip on the surface of the lead and then cutting out the cavity with a knife or other tool. The surface of the matrix and the lead exterior layer is 100 perforated with holes or slots 15, 15, see Fig. 2, by means of which the air from the underside of the work may be exhausted, so that the work will be held firmly in the depression in the matrix by atmospheric pressure on the outside of the work. The said holes are located preferably all over the surface of the lead facing so that the cavity may be 105 formed anywhere on the periphery.

Inside of the matrix is located a suction box D of segmental form open on its peripheral surface, but inclosed on all the other sides thereof so that when the air is exhausted from the interior of the suction box 110

the only openings through which air can enter will be the holes 15, 15 in the circumference of the rotating matrix. The suction box D is supported in brackets 18, 18, preferably formed integral therewith, the whole being supported upon the upper end of a slide 19 movable vertically in ways formed in the frame A. These ways are formed by means of guides 20, 21, secured to the corresponding portion of the frame by means of cap screws 22. The slide 19 is adjusted vertically by means of an adjusting screw 23 provided with a set nut 24. The slide after being adjusted is rigidly secured in place by means of a cap screw 25 movable in a slot 26 in the slide 19, the inner end of the said cap screw 25 engaging the frame A. The object of this adjustment is for the purpose of raising or lowering the suction box until its edges lie close enough to the inner surface of the cylindrical wall of the revolving matrix to prevent any serious leakage of air around the edges of the suction box and at the same time not to cause undue friction.

25 The suction box is provided at 27 with a pipe connection leading to an air pump, not shown, by means of which the air is exhausted from the interior of the suction box. On a bracket 29 extending upwardly from the frame A is pivotally supported a tool 30 which operates upon the surface of the piece of stock in the cavity or depression in the matrix. In the drawings I have shown this tool as a sand paper roll of the kind heretofore frequently employed for buffing or scouring leather. Said roll is caused to rotate by means of a belt 31 running on a pulley 32 connected to said tool 30. The tool is carried on one end of an arm 33 pivoted at 34 to said bracket 29, the other end of said arm extending rearwardly and being engaged by a pair of adjusting screws 35 and 36 by means of which the pressure of the tool on the work may be adjusted or varied as desired. At 38 is indicated a brush roll supported on said pivot 34 which serves to clear the stock of dust etc. after it passes out from under the tool 30. Said brush roll is driven by a belt 60.

50 The operation of my machine is simple and effective. The matrix is caused to rotate at suitable speed by the rotation of the shaft B. The operator places the piece of stock in the proper position in the cavity 14 in the matrix and as the edge of the cavity 14 advances over the suction box the vacuum therein causes air pressure on the outer surface of the stock which forces the stock down into the cavity filling it and holding the stock securely in place and in proper position for presentation to the tool 30. As the rotating matrix advances, such portions of the piece of work as protrude above the line of operation of the scouring tool are removed by it, so that the outer surface of the piece

of stock is left flat. The position of the stock in the matrix with relation to the scouring roll is plainly seen in Fig. 4. In cases where it is desired to bevel the edges of the pieces of stock the matrix cavity is made deeper than the thickness of the piece of stock so that the tool only contacts with the protruding edges. As the revolving matrix moves by the scouring roll and the end of the cavity in the matrix passes beyond the edge of the suction box, the work is released and drops out of the matrix. Since the pressure over the entire surface of the work in the cavity in the matrix is substantially uniform and as it may be varied according to the character of the stock by varying the degree of vacuum in the suction box, it is found that the work may be pressed uniformly into the entire cavity in the matrix and that it is held there securely during the operation so that work having smooth faces is produced. Also no marks are made on the work and the work is never injured or ruined by the instrumentalities which hold the stock in the cavity in the matrix while it is being operated upon.

As the stock is usually narrow and a sand paper roll considerably wider can be economically used, I provide means for sliding the sand paper roll relatively to the matrix, as shown in Fig. 5 to bring a different portion of the sand paper roll in contact with the work in the matrix. This consists in mounting the shaft 63 upon which the sand paper roll rotates so that it is slidable longitudinally in bearings 64 and 65 in the frame and providing at the end of the shaft 63 a collar 66 engaged by a fork 67 mounted on a screw 68 secured to the frame of the machine. On both sides of said fork 67 are placed thumb nuts 69 and 70 which may be screwed against the said fork 67 and will hold it securely in place. When it is desired to change the position of the sand paper roll, one of the nuts is loosened and the other screwed up to move the fork into contact with the nut and secure it in place again.

What I claim is:

1. In a machine of the character described, the combination with a tool of a stationary suction box having a periphery which is an arc of a circle, and a cylindrical matrix with a work receiving depression formed in its periphery, said matrix being caused to rotate and to bring the work receiving depression periodically over the suction box.

2. In a machine of the character described, the combination with an operating tool of a rotating perforated matrix having a cavity in the surface thereof to receive the work, said matrix having an unobstructed interior, a stationary segmental suction box open on its periphery and cooperating with the perforated periphery of the matrix and means

115

120

130

for adjusting the said suction box vertically to cause it to contact with the interior periphery of the said matrix.

3. In a machine of the character described, 5 the combination with an operating tool of a perforated matrix provided with a removable perforated facing of soft metal having a suitable cavity formed therein to receive the work, and a suction box coöperating

with said matrix to cause a piece of work in 10 the said cavity to be held therein by air pressure.

In testimony whereof I affix my signature, in presence of two witnesses.

DAVID N. ROBERTSON.
